PRESS DRIVE

Oscar Charles Roesen, Eastchester, N. Y., assignor to Wood Newspaper Machinery Corporation, New York, N. Y., a corporation of Virginia

Application December 11, 1929, Serial No. 413,287
Renewed July 29, 1932

3 Claims. (Cl. 101—220)

This invention relates to the driving of printing presses and printing press units.

The principal objects of the invention are to provide a drive which will eliminate the customary elaborate system of right angle shafts and bevel gears; to provide a drive which has convenient parts for driving other elements of the press, as for example, a fountain roll; to provide a construction in which the driving motor is most conveniently placed where it takes up no room outside the limits of the press, and to provide a construction in which the several units can be connected when in proper registration.

Other objects and advantages of the invention will appear hereinafter.

Reference is to be had to the accompanying drawings, in which

Fig. 1 is an end elevation of one printing press unit shown partly diagrammatically, and showing the application of this invention thereto;

Fig. 2 is a sectional view on the line 2—2 of Fig. 1, showing the unit in side elevation, and Fig. 3 is a plan of the lower part of the drive.

It is customary to drive printing presses and their units through an elaborate system of right angle shafts and bevel gears, involving considerable expense in manufacture and assembly, and also considerable attention to keep them in order. It is also customary to mount the motors outside the limits of the press where they take up room beyond that required for the press itself.

In accordance with this invention the motor 10 is mounted in brackets 10^a depending from the underside of the bed-plate 11 of the press, and thus not occupying any room outside the limits of the press itself. The motor can be located entirely underneath the bed-plate. The motor shaft 12 is provided with a bevel gear 13 meshing with a bevel gear 14 on a pilot shaft 15 extending along the press frame unit to unit. The gear 14 is loose on the shaft and adapted to be clutched thereto by a clutch 16 which can be operated in any desired way. The shaft 15 is supported by brackets 17 depending from the bed-plate. The object of this arrangement is to provide for connecting and disconnecting the unit shown. Another clutch of a similar nature is provided for the next unit, so that either unit may be left out of operation while others along the shaft 15 are operated.

For multiple operation it is obvious that the design of the clutch must be such that it can be engaged only when the incoming unit is properly registered with those with which it is being connected. Thus the several clutches have a definite and permanent relation to each other.

On the motor shaft 12 is a sprocket 20, which, through a sprocket chain 21, drives a sprocket 22 on an intermediate shaft 23. This shaft is

mounted on brackets 24 carried on the top of the bed-plate. On the intermediate shaft is mounted another sprocket 25 which, through a chain 26 and a sprocket 27, drives the shaft of the impression cylinder 28, the sprocket being mounted directly on that shaft. The other parts of the press in general are, or can be, driven by the usual gearing from the impression cylinder.

The intermediate shaft 23 can also be used, on account of its convenient location and speed, for driving other parts of the press, and for this purpose this shaft is shown as provided with a worm 30 driving, through suitable gearing, a shaft 31 at low speed, which in turn drives a shaft 32 connected to drive the fountain roll of the press.

By this arrangement it will be seen that the driving motor is conveniently placed and the drive to the press is direct through chains and sprockets, thus eliminating the usual more elaborate driving system. Furthermore, the fountain roll or other part of the inking mechanism, folder, or press can be driven from this mechanism through the shaft 32 because of its convenient location and speed reduction. The pilot shaft 15 is used to insure absolute synchronization of the two or more units when run in multiple. Any number of decks and folders may be synchronized in accordance with this system.

While I have illustrated and described only one form of the invention, I am aware of the fact that changes can be made therein by any person skilled in the art without departing from the scope of the invention as expressed in the claims. Therefore, I do not wish to be limited to the exact form shown, but what I do claim is:

1. In a printing machine, the combination with the bed plate of the frame of a motor supported by the bed plate below it, an intermediate shaft supported by the bed plate above it, a chain from the motor shaft to the intermediate shaft, an impression cylinder, a chain from the intermediate shaft to the impression cylinder, speed reducing means connected with said intermediate shaft and means for driving a fountain roll from the speed reducing means.

2. In a printing machine comprising several units comprising ink motions and impression cylinders, the combination of an individual motor for each unit, means for driving one impression cylinder of the unit with intermediate means between the motor and impression cylinder for driving part of the ink motion.

3. In a printing machine comprising several units, the combination of an individual motor for each printing unit, of an intermediate shaft, a chain driven from the motor and operating the intermediate shaft and a chain driven from the intermediate shaft and operating one of the impression cylinders of the press.
